Felis T. Segui, % Caravan Restaurant, Gorman, Calif.

Filed Oct. 10, 1960, Ser. No. 62,434

Term of patent 7 years

(Cl. D34—15)

FIG 1

The dominant feature of my design resides in the portion shown in full lines, the broken line portions being omitted in FIGURES 1 and 2 for convenience of illustration.

I claim:

The ornamental design for a revolving whistle toy, substantially as shown and described.
